CARPET.

No. 18,150.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,150, dated March 6, 1888.

Application filed January 26, 1888. Serial No. 262,076. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists, principally, of conventionalized leaf forms, some of which are large and prominent, while others are gathered into

groups or clusters. A few small circular flower forms occur among or between the 20 leaves. One large leaf has a general scroll shape and at its upper end spreads out and is divided by deep serrations into several broad lobes or parts. Another large scroll-shaped leaf is connected with a thick mass of leaves. 25 At the center of the design is a large group of scroll-shaped and fan-shaped leaves combined.

What I claim as new, and desire to secure by Letters Patent, is—

The design for carpets, consisting of the de- 30 sign substantially as shown.

JAS. L. FOLSOM.
